HEAT INTERCHANGER

Joseph Askin, Buffalo, N. Y., assignor to Fedders
Manufacturing Company, Inc., Buffalo, N. Y.

Application July 12, 1935, Serial No. 31,002

3 Claims. (Cl. 257—246)

This invention relates to heat interchangers, and it has particular reference to an apparatus which may be readily and effectively utilized for counter-flow heat exchange in such systems as 5 refrigeration plants.

The ordinary compressor-condenser-expander refrigeration system includes an expansion coil, in which the relatively warm liquid refrigerant is allowed to gasify with concomitant cooling, and 10 the expanded gases are then returned to the compressor and condenser for liquefaction and recirculation. Frequently, the service conditions are such as to permit some unexpanded liquid to pass through the expansion coil, resulting in the flooding of the compressor with its well recognized attendant disadvantages.

In order to circumvent such liquid return, and thereby make the system more efficient and to obviate the necessity of constant attention and 20 adjustment, the present invention proposes a heat exchanger which may be interposed between the expander and compressor, in such fashion that any liquid refrigerant tending to return to the compressor will do useful work in pre-cooling 25 refrigerant en route to the expander. More particularly, the heat exchanger of this invention is so devised as to make it readily applicable to existing installations, and is of a nature permitting its construction in the field, or where the 30 invention must be made without resort to expensive tools.

The various features and advantages of the present invention will become more apparent from a perusal of the following detailed description of a preferred embodiment, illustrated in the 35 accompanying drawing, wherein:

Fig. 1 is a view, partly in longitudinal section and partly in elevation, of the heat interchanger; and

Fig. 2 is a diagrammatic view, showing the installation of the invention in a refrigeration system.

As shown in Fig. 1, the interchanger is fabricated of two fitting units 10 connected by telescoped inlet and outlet tubes 11 and 12. Each 45 unit 10 is formed of a body 13 which is in the form of a reducing T having aligned branches 14 and 15 and an angular branch 16, all of which are exteriorly threaded. The larger branches 15 and 50 16 are formed with terminal male flares or bevels 17 and 18 and large interior communicating passages 19 and 21 respectively. The small branch 14 is formed with an opening 22 adapted to receive the small inlet tube 11 and the extremity of

this branch is provided with a female flare or interior bevel 23.

The outer tube 12 is flanged at both extremities, as indicated by the numeral 24, and it is assembled to connect the branches 15 by means of nuts 5 25 which are each formed with interior female flares 26 which force the tube flange 24 into fluid-tight engagement with the branch flares 17. The extremities of the inner tube 11 are likewise formed with flanges 27 which seat on the female 10 flares 23 of the branches 14. Couplings 28 secure these connections and they are each formed with a nut portion 29 having an interior male flare 31 adapted to engage one of the flanges 27 and remain in seated relation with the branch flare 14. 15 The free end of each coupling is formed with a threaded branch 33 having a male flare 34.

The fitting structures, above described, permit the formation of a heat interchanger with the aid of the simplest tools and operations. Hence, 20 the assembly may be made by the mechanics on the scene of the installation of an evaporator, condenser, or like device with which it is intended to cooperate.

In the process of assembling the interchanger, 25 the tube 12 is cut to the desired length and it is then flanged after the nuts 25 have been positioned thereon. One extremity of the small tube is likewise flanged, then engaged through the opening 22 in one of the fitting bodies 13, and 30 finally is secured by a coupling 28. The large tube 12 is then connected to both bodies by securing the nuts 25, and coincidental with this operation, the plain extremity of the small tube is projected through the opening 22 in the remaining 35 body, whence it projects from the branch 14. This extremity of the tube 11 is then cut off flush with the extremity of the branch 14 and it is flared by a suitable tool. The subsequent application of the remaining coupling 28 completes 40 the assembly.

The interchanger may be used as a regenerator in the suction line of a refrigeration system, as illustrated in Fig. 2. In this installation, an 45 evaporator 37 forms part of a refrigeration circuit including a supply conduit 11—A in which is positioned a metering device such as a thermostatic expansion valve 38. The expanded gases in the evaporator are directed to a suction 50 line 39 leading to the compressor (not shown) and, due to various conditions of operation, it often occurs that unexpanded refrigerant in liquid form is introduced into the suction conduit, resulting in a danger of injuring the compressor, 55

or at least in an undesirable waste or misdirection of energy.

The interchanger is interposed in both the supply and suction conduits to correct this condition.

5 As shown in Fig. 2, the supply conduit 11—A is cut and its ends are connected to the branches 33 of the couplings 28 by nuts 41. Similarly, the cut extremities of the suction conduit are secured to the branches 16 by nuts 42.

10 It will be observed that the liquid refrigerant, passing through the tubes 11 and 11—A, and the gas being withdrawn through the tube 12, are opposed in direction of flow, so that a greater mean temperature differential between the fluids 15 is attained, resulting in a greater heat transfer.

In the practical operation of the usual refrigeration system the incoming or supply liquid is comparatively warm, the temperature varying between 80° and 110° F., while the returned gas 20 varies from freezing to 50° F., depending upon the operating conditions. Under such circumstances, a mutually advantageous heat exchange is effected between the liquid and gas through the wall of the tube 11, wherein the liquid is 25 cooled to a more efficient state before being exposed to expansion in the evaporator, while the outgoing gas is accordingly heated, causing liquid refrigerant to expand and to do useful work before being directed back to the compressor.

30 It will be understood that the interchanger is not limited to the use herein described, but that it may be advantageously employed wherever heat exchange between fluids is indicated.

I claim:

35 1. A heat interchanger comprising a pair of conduits one of which is disposed within the other in spaced relation thereto, fittings at the ends of said conduits for permitting liquid to flow simultaneously and independently through each, 40 said fittings comprising a body having a passage therethrough for the reception of the inner conduit, a beveled face on the end of said body, a nut

disposed around the outer conduit and adapted to be secured to said body adjacent said beveled face, said nut being internally formed with a beveled seat adapted to be slightly spaced from said beveled face, said outer conduit being flared 5 to occupy the space between said body and nut, whereby said outer conduit is fixedly secured to said body when said nut is assembled thereon, said body being formed at its opposite end with means for securing said inner conduit thereto in 10 fluid tight relation, and a branch passage formed in said body to establish fluid communication with the space between the inner and outer conduit.

2. A heat interchanger comprising a pair of 15 fitting units, each including a T fitting having aligned branches and an angular branch, one of said aligned branches having a passage therethrough terminating in a female flare, the remaining branches having larger communicating passages and being formed with male flares, a tube extending through the aligned branches of both fittings and formed with a flange on each extremity engaging the female flares thereon, a coupling having a nut portion securing each flange 25 to the adjacent fitting, a larger tube enclosing the first tube and formed with flanges on each end engaging the male flares of the aligned branches of the fittings, and nut members securing the last flanges to the fittings. 30

3. A heat interchanger comprising a pair of fitting units, each including a T fitting having aligned branches and an angular branch, one of said aligned branches having a passage therethrough, the remaining branches having larger 35 communicating passages, a tube extending through the passages in the aligned branches of both fittings, a larger tube enclosing the first tube and engaging the opposed branches of the fittings, and detachable connections securing the tubes to 40 the fittings.

JOSEPH ASKIN.
